ANDREW M. HUNT, OF BERKELEY, AND DONALD E. FOGG, OF OAKLAND, CALIFORNIA.

APPARATUS FOR COOLING AND SCRUBBING GASES.

1,327,599.

Specification of Letters Patent.

Patented Jan. 6, 1920.

Application filed May 25, 1914. Serial No. 840,756.

To all whom it may concern:

Be it known that we, ANDREW M. HUNT, of Berkeley, Alameda county, State of California, and DONALD E. FOGG, of Oakland, 5 Alameda county, State of California, both citizens of the United States, have invented new and useful Improvements in Apparatus for Cooling and Scrubbing Gases, of which the following is a specification.

10 This invention relates to a process for cooling hot gases and cleansing hot gases carrying solid or liquid particles or condensable vapors and relates also to a self contained device for the application of this 15 process.

The process involves generally the cooling and scrubbing of hot gases carrying solid or liquid particles or condensable vapors which consists in passing them through an 20 inclosed space where they are showered with a liquid. Said inclosed space contains a set of pipes through which cooling water circulates. The scrubbing liquid performs a 25 double function, it first knocks down any solid or liquid particles and being broken into a fine spray by the current of the gases presents a greatly increased surface for absorption of heat from the gases, and this fine spray then comes in contact with the cooled 30 pipes, gives up its heat and is blown off to pick up more heat from the gas. In other words, the mist of the scrubbing liquid plays the part of an abstractor of heat from the gas, which it conveys to and delivers 35 up to the cooling pipes.

Figure 1 of the drawing is a vertical section of an apparatus suitable for practising the process.

Fig. 2 is a section on line X—X of Fig. 1. 40 A indicates a tower or other inclosed space having an inlet 2 for the hot gases at some point adjacent to but preferably above the bottom of the tower; the cooled scrubbed gases issuing from the top of the tower 45 through the stack 3. 4 is a header or water column arranged centrally within the tower and constitutes a reservoir to contain cold water for cooling the gases, which water is circulated in coils 5, preferably of lead ar- 50 ranged in pancakes in the annular space 6 between the header 4 and the walls of the tower. If desired the space in the header above and below the gas inlet 2 may be divided by a partition 7 forming an upper 55 water chamber 8, with which the banks of pancake coils 5 connect, and a lower water

space or reservoir 9 with which the banks of pancake coils 5' below the gas inlet 2 connect; the water in the compartment 9 usually being colder than that within the compartments 8.

Any appropriate form of construction may be employed for connecting the coils 5—5' with the header 4. Preferably though, the header 4 is in shape in cross-section of that of a snail, as shown in Fig. 2, with the pipes 5—5' heading through the vertical radial wall 10 with each pipe provided with a regulating valve 11 by which the quantity of water passing through the coils 5—5' may be regulated according to the temperature at which it is desired to keep them.

Any appropriate arrangement may be employed to handle the cooling water through pipes 5—5'. As here shown, these several pipes after taking their water from the header delivered it into a stand pipe 12, which discharges into a sump 13 and after cooling is delivered by appropriate means, as a centrifugal pump 14, by separate conduits 15—16 leading respectively to the compartments 8—9, so that the cooling water is continually circulated, entering as cold water in the compartments 8—9; discharging as hot water through the header 12, cooled and thence re-circulated.

As before stated, there are two series of banks of coils 5—5', the former above the gas inlet 2, and thereby arranged directly in the path of the ascending gases; and the other series, 5' being below the inlet 2, and not, to any appreciable degree, coming in contact with the gases passing through the apparatus. The function of these two series or sets of coils will be referred to later.

Arranged in the upper part of the apparatus, so as to spray a suitable liquid downwardly upon all the pipes 5—5', is a suitable spraying device, such as the perforated pipe 17, which is connected by a pipe 18 with the centrifugal pump 19, which latter has its suction side connected with the bottom of the tower A by the pipe 20, so that a continuous circulation of spraying liquid may be kept up through the apparatus; the character of this scrubbing liquid varying with the different gases handled and the results to be accomplished.

The scrubbing liquid is broken up into a mist by the velocity of the gas and exposes an enormous area to the gas for heat absorption by the scrubbing liquid. The scrubbing

liquid, in its misted form, then impinges against the lead pipes 5, condenses thereon, and drips off to be again disrupted. The heat transfer through the lead coil is really from liquid on the outside to liquid on the inside instead of from gas on the outside to liquid on the inside.

In such an inclosed space or tower in actual service, the lower pancake coils 5 closest to the inlet 2 of hot gases absorb a great amount of heat and the absorption of each succeeding set of coils decreases as the temperature of the gases falls. The same thing is true of the lower sets of cooling coils 5' below the hot gas inlet the function of which sets of coils is solely to cool the hot liquid formed by condensation of spray after same has completely passed through the hot gases. To meet this condition of variable heat absorption by the separate sets of coils, the amount of cooling liquid passed through each individual set of cooling coils is carefully regulated and in this manner any temperature of exit gases desired down to the temperature of the cooling water itself may be maintained and closely controlled.

The amount of liquid actually in contact with the gases is small, and being constantly recirculated, it is a comparatively simple matter to settle out the suspended solids and save them if desirable.

A sufficient quantity of the liquid is maintained in circulation through the inclosed space to absorb the entire quantity of heat which is to be removed without reference to the cooling action of the pipes upon the gas direct; the function of the pipes being primarily to cool the liquid spray.

Having thus described our invention what we claim and desire to secure by Letters Patent is—

1. An apparatus for cooling and scrubbing hot gases, consisting of a tower having a gas inlet at one side and above the bottom thereof, and a gas outlet at the top, banks of cooling coils in the tower above and below the gas inlet, means for spraying a liquid on the pipes and counter to the currents of gases, a header in the tower with which the cooling pipes connect, and means for maintaining a constant circulation, with

intermittent cooling of a second liquid, through said header and pipes.

2. An apparatus for cooling and scrubbing hot gases, consisting of a tower having a gas inlet and a gas outlet, a set of cooling coils above the gas inlet in the path of the hot gases, means for spraying a liquid into the path of the hot gases and upon said coils, and means including a set of cooling coils below the gas inlet and out of the path of the entering hot gases for cooling the spraying liquid, a header in the tower with which the cooling pipes connect, means for maintaining a constant circulation of a second liquid, with intermittent cooling thereof, through said header and pipes, and means for returning the cooled spraying liquid again to the top of the tower for re-use.

3. An apparatus for cooling and scrubbing hot gases, comprising a chamber having a gas inlet intermediate its top and bottom, a gas outlet at its top, banks of cooling coils in the tower above and below the gas inlet, means for spraying a liquid over said coils, a header with which said cooling coils connect, said header comprising two portions feeding the coils above and below the gas inlet respectively, and means for circulating cooling liquid through said header and coils.

4. An apparatus for cooling and scrubbing hot gases, comprising a tower having a gas inlet intermediate its top and bottom, a gas outlet above said gas inlet, a series of distinct cooling coils above and below the gas inlet, means for spraying a liquid over said cooling coils, a header with which said coils connect, means for circulating cooling liquid through said coils and means outside said tower for independently regulating the flow of liquid through each coil, whereby the coils may be maintained at different temperatures.

In testimony whereof we have hereunto set our hands in the presence of two subscribing witnesses.

ANDREW M. HUNT.
DONALD E. FOGG.
